UNITED STATES PATENT OFFICE.

FRANK J. SCHLEICHER, OF ST. LOUIS, MISSOURI.

PAPER BOX.

Application filed August 10, 1925. Serial No. 49,434.

My invention relates to the manufacture of boxes and particularly to the manufacture of heart-shaped cardboard boxes such as are used more particularly for candy.

5 The object of my invention is to lessen the cost of such boxes by eliminating the hitherto costly hand-manufacture necessitated by forming the sides of the box in a curve which made it impossible, from a practical 10 standpoint, to form the bottom and sides of the box in one piece or to make the box by automatic machinery. I accomplish this object by making the sides of the box in straight sections approximately following a 15 heart shape contour, and applying a base or cover sheet to the box which is heart shape in contour, and so nearly coincides with the side wall of the box that there is no unsightly difference between the wall of the box 20 and the base or cover.

In the accompanying drawings which illustrate a selected embodiment of my invention—

Figure 1 is an outline of the blank from 25 which the box is made, the scoring and bending lines being indicated by dot-and-dash lines.

Figure 2 is a top view of the box with the side wall forming portions bent into 30 their proper position.

Figure 3 is a top view of the completed box.

Figure 4 is a perspective view of the box with a similarly made lid assembled there- 35 with.

The blank illustrated in Figure 1 consists in a body portion 1 roughly heart-shaped in outline and more specifically comprising a rear portion 2 in the shape of a rearwardly 40 tapering trapezoid, the length of which substantially exceeds the width, a contiguous middle portion 3 in the shape of a forwardly tapering trapezoid of the same base length as portion 2 but substantially wider 45 than portion 2, and a contiguous forward portion 4 in the shape of a triangle with an angle directed forwardly. Each of the exposed edges of the body portion 1 is provided with a rectangular tab 5, the length of 50 which corresponds to the length of the respective straight portion and the width of which corresponds to the desired depth of the box and of course is uniform for all the tabs.

55 Obviously, the tabs 5 may be bent at right angles to the bottom 1 to form a continuous

side wall for the box as indicated in Figure 2. A strip of paper 6 is then pasted around the sides of the box to hold the tabs 5 in their wall forming positions. The top edge 60 of said strip may be turned over the top edges of the tabs and pasted to the inside wall surface in the usual manner.

A truly heart-shaped base 7 is then applied to the outside surface of the box bottom 1 and it will be noted that the outline of base 7 substantially circumscribes the polygonal box body, the slight margins between the intermediate portions of the straight side wall sections of the box and the edge of the curved base forming a continuous projecting lip, such as is ordinarily provided on heart-shaped boxes having curved walls, but varying in extent throughout its length.

In the box described, the rear portion consists of a straight wall 8 extending in a straight line from a point on the upper outer edge of one lobe of the curved base 7 past the rear intersection 9 of the base lobes, past the upper intersection of the lobes at the center of the base to a point on the upper outer edge of the other lobe. Relatively short side wall sections 10 extend from the ends of portion 8 outwardly and forwardly and longer side wall sections 11 extend forwardly and inwardly from the ends of sections 10 and join at 12 in a forwardly directed point adjacent to the lower intersection of the lobes.

While I have described the bottom and side walls of a box, obviously the same structure may be duplicated to form the box lid having portions 7^a, 10^a, 11^a, and 12^a corresponding to the similar portions of the box proper.

The construction of a heart-shaped box with straight wall sections without departing from the general appearance of the box and the retaining of a heart-shaped bottom and lid with curved edges makes it possible to supply the trade with heart-shaped boxes at a fraction of the cost of such boxes heretofore. Obviously the exact number of straight sections may be varied and I contemplate such and similar modifications in the commercial development of my invention as are included in the scope of my claims.

I claim:

1. In a box, a base with a curve heart-shaped contour, a bottom sheet mounted thereon, side walls integral with said sheet

and comprising a straight rear portion slightly shorter than the greatest width of the box, relatively short straight portions at the end of said rear portion and extending 5 outwardly and forwardly therefrom and straight portions at the ends of said relatively short portions and extending inwardly and forwardly therefrom, to unite in a forwardly directed point.

- 10 2. In a cardboard box, a base sheet with a heart-shaped curved contour, a bottom sheet mounted on said base and including integral elements bent upwardly to form a rear wall, extending in a straight line between points 15 near the upper outer edges of the respective lobes of said base sheet and past the upper intersection of said lobes, and side walls each

extending in straight lines downwardly and outwardly and then forwardly and inwardly toward the lower intersection of said lobes. 20

3. In a cardboard box, an inner bottom element with a plurality of straight side walls formed integrally therewith and bent upwardly and disposed in a general heart-shaped arrangement about the edges of said element and another bottom element having a heart-shaped curved contour circumscribing the lower edges of said walls and attached to said inner bottom element. 25

30 In testimony whereof I hereunto affix my signature this 5th day of August, 1925.

FRANK J. SCHLEICHER.
